DUAL MANIFOLD EQUALIZER

David Firth, Flint, Mich., assignor to Borg-Warner Corporation, Chicago, Ill., a corporation of Illinois

Application January 21, 1938, Serial No. 186,170

4 Claims. (Cl. 123—52)

This invention relates to internal combustion engines and particularly to a novel arrangement for supplying fuel thereto.

The provision broadly of an equalizing passage between the inlets of a dual manifold together with a valve for controlling this passage under certain conditions has been disclosed heretofore as, for example, in the patent to Timian No. 1,763,726 and in the patent to Paton No. 1,872,800; however, I have discovered an improved arrangement of this valve together with means for controlling the same under most critically important conditions not heretofore disclosed or appreciated.

I have discovered that in a dual feeding system the respective manifold portions should be in communication under certain very specific conditions and individualized or separated from communication with each other under certain other very specific conditions. I have further found that the degree of depression in the manifold itself is the most accurate index throughout the entire range of operation as to when these dual manifolds should be in communication or individualized. Still further, I have found that the valve controlling this communication should be operated from open to closed position quickly and in response to a predetermined degree of depression within the manifold irrespective of whether this depression is caused by a quick opening of the throttles to only partially full open position; by the faltering of the engine during idling; or by the fuel opening of the throttles.

A duplex or two passage carburetor feed will produce very little more maximum power than a single feed, but between engine speeds of from about 800 R. P. M. to about 2800 R. P. M., the duplex feed shows a definitely increased torque over the single passage carburetor feed. This gives a quicker acceleration especially on accelerations from about 10 to about 60 miles per hour, a better hill climbing performance and a marked improvement generally in what is referred to in the art as a better "driving feel." These improved results flowing from individualized or dual feeds are not due to the increased size of the carbureting passage but are a result of the reduction of surge in the manifold.

On the other hand it is found that under light load conditions as when the motor is idling normally or the car moving along under light load and the throttles only partly open, the very high vacuum created within the respective manifold portions is higher than that conducive to the most efficient operating conditions and

hence under these circumstances it is desirable to effect communication between the dual manifolds for the purpose of equalizing the pressure therein.

It is the object of my invention to provide an arrangement of means for carrying into effect the above enumerated discoveries. These and other objects of my invention will more fully appear from the following description taken in connection with the accompanying drawings, wherein:

Fig. 1 is an elevation partially in section of a preferred embodiment.

Fig. 2 is a vertical section taken on the line 2—2 of Fig. 1.

Fig. 3 is a plan view with the carburetor removed and showing certain parts in section.

Referring in detail to the drawings, I have shown for purposes of illustration, an internal combustion engine 10, indicated in dotted lines, and having eight cylinders arranged to be supplied with fuel in two groups of four cylinders each; cylinders one, two, five and six comprising a first group, and cylinders three, four, seven and eight comprising a second group. A dual manifold indicated generally at 10 is formed with a first conduit 11 therein communicating at its right end portion with flange connector 12 for connection with cylinders 1 and 2 and at its left end portion with flange connector 13 for connection with cylinders seven and eight and provided intermediate its ends with a vertical conduit portion 14 for cooperation with one of the dual passages of a carburetor (later to be described).

A second conduit portion 15, the righthand end of which terminates in a connector flange 16 for connection with cylinders three and four, the lefthand end of which terminates in connector flange 17 for connection with cylinders five and six provided with a vertical conduit portion 18 likewise for cooperation with a second dual passage of a carburetor. It is important to note that vertical conduit portion 14 and vertical conduit portion 18 are each defined in part by a common vertical wall 19.

Mounted above vertical conduit portions 14 and 18 is a carburetor 20 of the type having dual air passages 21 and 22 cooperating with conduit portions 14 and 18 respectively and provided with throttles 23 and 24 respectively, mounted on a common shaft 25 under the control of the usual manual connections including crank 26.

This carburetor is provided with the usual fuel supply including fuel bowl 27, fuel nozzles 28, etc., a detailed showing of which is omitted for purposes of simplification.

The arrangement thus far described is well known and no claim is here made thereto other than in combination with the novel equalizer hereinafter described.

5

Equalizer

Common dividing wall 19 has a circular port 29 formed therein and supplied with a butterfly valve 30, mounted on shaft 31, the opposite ends of which are journaled in the wall 19. The right end of shaft 30 (see Fig. 3) extends through the outer wall of manifold 10 and supports one end of crank 32, the other end of which is connected by a link 33 with a bell crank 34 pivotally mounted on a bearing 35 attached to manifold 10. A second link 36 connects the other end of the bell crank 34 with the stem 37 of a piston 38, operating within a cylinder 39. This cylinder is attached to the first named portion 11 of the manifold and has its interior in communication therewith through passage 40 for subjecting piston 38 to the varying pressures within the manifold. The left end of cylinder 39 is provided with threaded sleeve 41 serving as a sealed bearing for stem 37. Cylinder 39 is further provided with carefully calibrated compression spring 42 the left end of which is in contact with piston 38 and the right end of which is in contact with washer 43 carried on the inner end of screw 44 threadably mounted in threaded closure plug 45, serving as a means for accurately adjusting the degree of compression of spring 42. Screw 44 is maintained in its position of adjustment by lock nut 46.

35

Operation

With the throttles 23 and 24 in their near closed idle position and the motor idling normally, a vacuum exists in the manifold portion 11 effective to draw piston 38 to the right and 40 maintain valve 30 in a partial or full open position to thus effect an equalization of the pressure between manifold portions 11 and 15. If the throttles are now quickly opened either to partial or full open position, the vacuum within manifold portion 11 is suddenly dropped and spring 42 becomes effective to move piston 38 to the left, effecting a closure of valve 30 to thus 45 shut off communication through wall portion 19 and individualize the fuel supplies to the respective groups of cylinders. It is very important to note that this has the immediate result of rendering the full vacuum created by each group of cylinders effective upon its individual fuel supply. This condition maintains until the vacuum 50 is built up to a degree where it is again effective to move piston 38 to the right and thus reopen valve 30 for again equalizing the pressures within the respective manifold portions.

The degree of manifold vacuum is the most 55 accurate index of the conditions existing therein demanding a transition from a condition of equalization to a condition of individualization and vice versa, and therefore since spring 42 and screw 44 are capable of fine adjustment, this transition can be perfectly controlled. In accordance with my invention, valve 30 is thus rendered entirely dependent in its operation upon the vacuum condition within the manifold and 60 is completely independent of any mechanical correlation with the throttle position, such as is inherently the case with the structures disclosed in the aforementioned patents.

Good results will be obtained if spring 41 is 65 made to operate at a pressure in the manifold

of about six inches of mercury or below to individualize the fuel feeding passages.

While I have disclosed my invention in connection with a specific embodiment thereof, it is to be understood that this is by way of illustration only; that many other applications may be made within the teaching of my invention; and that it is my desire to be limited only as indicated by the appended claims which should be given a scope as broad as the prior art will 10 permit.

I claim:

1. In a multi-cylinder internal combustion engine, the combination of an intake manifold having two spaced inlet passages serving different groups of cylinders, individual carbureting means supplying each of said passages including a throttle valve in each means, control means for said valves, and a third valve providing communication between said carbureting means, means urging said third valve toward closed position, control means for acting in opposition to said last named means, said third valve urging means being operable in response to a relatively low vacuum such as occurs upon sudden partial or full opening of said throttle valves to effect a quick closure of said third named valve to thereby bring about individualized feeding of said groups of cylinders, said control means being operable responsive only to the development of a relatively high vacuum within said manifold such as occurs either with the motor operating under light load with the throttles in a definite partly open position or with the throttles in idling position, to effect the opening of said third named valve to bring about communication between said fuel supply passages whereby to equalize the pressures therein under conditions of relatively high vacuum.

2. In a multi-cylinder internal combustion engine the combination of an intake manifold having two spaced inlet passages serving separate groups of cylinders, individual fuel supply conduit means for each of said inlet passages including a throttle valve in each conduit, an additional valve for controlling communication between said inlet passages, resilient means for urging said additional valve to closed position to thus shut off communication between said inlet passages and thus individualize the fuel supplies to said respective groups of cylinders when the degree of vacuum in the manifold is relatively low, means operable in response to the occurrence of a predetermined degree of relatively high vacuum, such as occurs with said throttles in nearly closed positions and the motor idling, or with the throttles in an intermediate position with the motor running under light load, to effect the opening of said additional valve against the resistance of said resilient means to thus bring about communication between said inlet passages to thereby effect equalization of the pressures in said passages, said means being further operable upon a subsequent decrease of vacuum to permit said resilient means to again effect the closure of said additional valve to again individualize said feeds.

3. The arrangement as defined in claim 1 wherein said control means for said third valve comprises a cylinder, a piston in said cylinder, a spring in said cylinder having predetermined resilient characteristics and effective to move said piston in one direction in said cylinder, said cylinder being in communication with said manifold whereby said piston is subjected to the vacuum

conditions therein for moving the same against said spring, and operating connections between said piston and said equalizer valve for operating the same in accordance with the vacuum conditions existing in said manifold.

5 4. The arrangement as defined in claim 1 wherein said control means for said third valve comprises a cylinder, a piston in said cylinder, a spring in said cylinder having predetermined 10 resilient characteristics and effective to move said piston in one direction in said cylinder, said cylinder being in communication with said mani-

fold whereby said piston is subjected to the vacuum conditions therein for moving the same against said spring, operating connections between said piston and said equalizer valve for operating the same in accordance with the vacuum conditions existing in said manifold, and adjusting means for adjusting the degree of compression of said spring for rendering said control means responsive to various vacuum conditions existing in said manifold.

5 10 DAVID FIRTH.
